UNITED STATES PATENT OFFICE.

MARTIN V. HAMMACK, OF THALIA, VIRGINIA, ASSIGNOR OF ONE-HALF TO
CEPHUS O. GRIMES, OF PORTSMOUTH, VIRGINIA.

DESIGN FOR A PICTURE-FRAME.

SPECIFICATION forming part of Design No. 35,935, dated June 10, 1902.

Application filed March 29, 1902. Serial No. 100,626. Term of patent 7 years.

To all whom it may concern:

Be it known that I, MARTIN V. HAMMACK, a citizen of the United States, residing at Thalia, in the county of Princess Anne and State of Virginia, have invented a certain new and useful Design for Picture-Frames, of which the following is a specification.

The object of my said invention is to provide a design for picture-frames of a highly ornamental and attractive character.

The accompanying drawing shows a picture-frame of my design in elevation.

Said frame consists of an outer ring 1, surrounded by a border of diamond-shaped plates which project across said ring, the center of the diamond-shaped plates being on a line with the circumference of said ring. Within said ring 1 is mounted a series of smaller rings 2, connected therewith at one edge. Within said series of rings 2 is a larger ring 3, surrounded by a border of diamond-shaped points extending from its periphery outwardly, several of which points are connected with several of said rings 2, whereby

said ring 3 is supported. In the design there are ten of the small rings 2, five on the upper and five on the lower side of the design, connected by small diamond-shaped plates 4, and the upper and the lower series of said rings are connected by a star-shaped plate 5 on each side.

The several rings 2 and the central ring 3 are each formed to receive a picture, the rings and the surrounding ornamentation constituting the frame for said group of pictures.

Having thus fully described my said design, what I claim as new, and desire to secure by Letters Patent, is—

The design for a picture-frame, as herein shown and described.

In witness whereof I have hereunto set my hand and seal, at Washington, District of Columbia, this 26th day of March, A. D. 1902.

MARTIN V. HAMMACK. [L. S.]
